US00D590431S

(12) **United States Design Patent**
Chen

(10) **Patent No.:** **US D590,431 S**
(45) **Date of Patent:** **** Apr. 14, 2009**

(54) **EYEGLASSES**

(75) Inventor: **Ward Chen**, Pomona, CA (US)

(73) Assignee: **Jay-Y Enterprises Co., Inc.**, Pomona, CA (US)

(**) Term: **14 Years**

(21) Appl. No.: **29/248,350**

(22) Filed: **Aug. 11, 2006**

(51) **LOC (9) Cl.** **16-06**

(52) **U.S. Cl.** **D16/314**

(58) **Field of Classification Search** **D16/101, D16/300-342; D29/109-110; D24/110.2; 351/41, 44, 51-52, 62, 158, 92, 103-123, 351/140, 153; 2/426-432, 447-449, 441, 2/434-437**

See application file for complete search history.
